UNITED STATES PATENT OFFICE

WILLIAM A. JONES, OF WEST NEW BRIGHTON, NEW YORK, ASSIGNOR TO THE BAB-COCK & WILCOX COMPANY, OF BAYONNE, NEW JERSEY, A CORPORATION OF NEW JERSEY

METHOD OF MAKING DRUMS

Application filed March 19, 1926. Serial No. 86,110.

My invention will be best understood from the following description and the annexed drawing, in which Fig. 1 is a longitudinal section of an illustrative form of drum embodying my invention; Fig. 2 is a section on the line 2—2 of Fig. 1, and Fig. 3 is an enlargement of one of the ends of Fig. 1 and illustrates the formation of this end in accordance with my method.

Like reference characters indicate like parts in the several views.

The drum illustrated in Figs. 1 and 2 is a form which is useful in high pressure steam boilers, this drum having a cylindrical shell 10, with its ends closed in in a manner to be described more specifically hereinafter, preferably with a manhole 11 at each end of the drum (though such a manhole at one end only will sometimes be sufficient), this manhole being closed, in the illustrative form, by a known form of manhole cover 12 seated against a gasket seat 13 which, in the illustrative form, is circular and is machined on the interior of the drum head. The cover 12 is held in place in the usual manner by bolts 14 extending through straps 15 extending across the exterior of the manhole. The particular form of manhole cover is no part of my present invention and further description thereof will be unnecessary to those skilled in the art. If the drum 10 is used as a boiler drum, tubes, such as 16 and 17, will enter the cylindrical portion of the drum in the usual manner, one form of which is shown in Figs.

1 and 2.

Preferably, in forming the drum, I first provide a cylindrical shell with its walls of substantially uniform thickness throughout its length and then force the end of this shell inward toward the axis of the shell and, at the same time, toward the opposite end of the shell. In other words, the end 18 of the shell is carried inward approximately along the curved line 19 to the full-line position in Fig. 3, with the metal originally at the point 18, positioned at about the point 20 at the periphery of the desired manhole opening. The metal in the cylindrical wall is bent, in effect, around a point, such as 20 or 21, of

the shell 10.

By forcing the metal inward and longitudinally of the drum in this manner, it is obvious that the metal of the drum head being formed will be increased in cross-section in accordance with the distance toward the axis of the drum to which any particular part of the shell 10 is moved, since the section must make up in thickness what it is losing in circumference. It will also be obvious that the head will have a continuous convex curvature, which is more desirable than the partly convex and partly concave curves heretofore found in drums of this sort.

The metal may be forced into the full-line position of Fig. 3 in several ways, but preferably I do this by a series of blows, as with a steam hammer, the drum being rotated between the blows, so that the net result is a series of blows applied to the end 18 of the shell and successively around it, such blows being struck in directions at an angle to the cylinder axis and toward the opposite end of the shell. I have indicated on the drawings in dotted line positions 18^a and 18^b, the general shape that the drum head of the illustrative embodiment will occupy as it is being forced into its final position. It should be understood, however, that, instead of this series of blows, the metal may be forced into its final position by a hydraulic press or by rolls. After the drum is forced inwardly and longitudinally to the position required to get the desired diameter of hole, the cover seat 13 is formed on the inside of the drum to receive the cover 12.

Preferably, I form the drum head into a hemispherical shape, though such shape may, if desired, be more or less conical, any surface of revolution having its curves all convex giving some of the advantages of my invention, provided it is such that in forming it, the metal of the shell wall assumes a section in which the thickness of the metal gradually increases from that of the shell wall to a maximum at the periphery of the manhole opening.

In a shell formed in the manner described above, when internal pressure is applied, the unit stresses in the metal adjacent the manhole opening are substantially the same as those in the cylindrical portion of the shell 10.

when internal pressure is applied to the drum. With the proportions shown in the drawing, the strength of the hemispherical head throughout and particularly at the edges of the opening, is actually greater than the strength of the cylindrical shell.

While preferably the drum head will be formed directly on the end of a long cylindrical shell so as to make a seamless drum, it is 10 obvious that my method may be applied to the making of drum heads which would then be riveted into cylindrical drum shells or otherwise attached to them.

I claim:

15 1. The method of forming a continuous walled drum having a hole in one end thereof which comprises forming a shell with a wall of uniform thickness, forcing the end of the shell inwardly toward the axis of the shell 20 until the end edge of the shell reaches the diameter of said hole, thickening the shell around said hole by forcing said end of the shell toward the opposite end thereof, and forming a cover seat around the hole inside 25 the drum.

2. The method of forming a continuous walled drum having a hole in one end thereof which comprises forming a shell with a wall of uniform thickness, forcing the end of the shell inwardly toward the axis of the shell 30 until the end edge of the shell reaches the diameter of said hole, simultaneously thickening the shell around said hole by forcing said end of the shell toward the opposite end thereof, and forming a cover seat around the hole inside the drum.

3. The method of forming a continuous walled drum having a hole in one end thereof 40 which comprises forming a cylindrical shell with a wall of uniform thickness, forcing the end of the shell inwardly toward the axis of the shell until the end edge of the shell reaches the diameter of said hole, simultaneously thickening the shell around said hole by forcing 45 said end of the shell toward the opposite end thereof, shaping the end of the drum into an externally convex surface of revolution, and forming a cover seat around the hole inside the drum.

WILLIAM A. JONES.
